(57) CLAIM

We claim the ornamental design for a hammock, as shown and described.

DESCRIPTION

FIG. 1 is a perspective view of the hammock;
FIG. 2 is a head end view of the hammock;
FIG. 3 is a foot end view of the hammock;
FIG. 4 is a top view of the hammock;
FIG. 5 is a side view of the hammock;
FIG. 6 is a perspective view of the hammock according to an alternative embodiment of the present design;
FIG. 7 is a head end view of the hammock shown in FIG. 6;
FIG. 8 is a foot end view of the hammock shown in FIG. 6;
FIG. 9 is a top view of the hammock shown in FIG. 6; and,
FIG. 10 is a side view of the hammock shown in FIG. 6.
The broken lines in the drawings illustrate portions of the hammock that form no part of the claimed design.
